UNITED STATES PATENT OFFICE.

CHARLES H. WOLFORD, -OF SALEM, OHIO.

HEN'S NEST.

No. 911,103.

Specification of Letters Patent.

Patented Feb. 2, 1909.

Application filed March 27, 1908. Serial No. 423,607.

To all whom it may concern:

Be it known that I, CHARLES H. WOLFORD, a citizen of the United States, residing at Salem, in the county of Columbiana, State of Ohio, have invented certain new and useful Improvements in Hens' Nests; and I do hereby declare the following to be a full, clear, and exact description of the invention, such as will enable others skilled in the art to which it appertains to make and use the same.

This invention relates to an improved hen's nest.

The aim of my invention is to provide a nest so constructed that the eggs may be collected in a receptacle below the nest from which they may be readily removed.

In the accompanying drawings, Figure 1 is a vertical sectional view of a hen's nest embodying my invention. Fig. 2 is a transverse sectional view of the housing, above the nest. Fig. 3 is a sectional view of the nest board, on line 3—3, Fig. 1.

In my present invention, I aim to provide a hen's nest constructed so that the eggs as soon as laid, will roll from the nest into a receiving tray, thereby preventing broody hens from setting upon the eggs, as well as preventing the eggs being broken or eaten by the hens.

In its operative embodiment, my invention includes a base 5, a front panel 6, a back 7, and the sides 8 and 9, the side 9 being provided with an entering opening 10 through which the hens enter the nest. The upper edge of the sides 8 and 9 incline upwardly and support the top 12 to which by means of hinges 13 the lid 14 is secured. The rear panel 7 is provided with an opening 15 through which the head of a suitable nail or hook may be introduced in supporting the nest.

Within the bottom of the housing is held a tray 16 having the knob 17 by means of which this tray may be drawn from the housing. Centrally this tray is provided with the puff 18 formed by means of hay, straw or some other like material over which

is drawn and secured a suitable fabric 20 fastened to the bottom 21 of the tray, as 50 well as to the sides.

Removably held within the housing and immediately above the tray 16 is a nest board 25 having a dished upper surface covered by means of the fabric 28 and being 55 centrally provided with an opening 26 which flares outwardly as shown at 27. This nest board has its edges beveled as is disclosed in Fig. 1 so that the same may be removed after raising the lid 14. At suitable points 60 this nest board as well as the housing is perforated so that the supporting pins 30, 30, may be carried through openings within the sides of the housing to removably support 65 this nest board.

In referring to the drawings it will be noticed that the puff is immediately below the opening 26 so that as the egg is laid and drops through the opening it encounters the puff and is gently directed into the tray. 70

My construction method permits the housing being kept clean and free of parasites.

And having thus described my said invention, what I claim as new and desire to secure by U. S. Letters Patent is— 75

A hen's nest comprising a housing having an entering opening upon one side, a lid secured to the top of said housing, a removable tray within the bottom of said housing, a puff within the center of said tray, and a 80 nest board having a dished upper surface with a central flared opening, said nest board upon the bottom being flared around said opening, said nest board being bevel edged and having suitable pin openings, 85 said housing also having suitable pin openings, and pins within said openings to removably hold said bevel edged nest board, all arranged as set forth.

In testimony whereof, I affix my signature, 90 in presence of two witnesses.

CHARLES H. WOLFORD.
